UNITED STATES PATENT OFFICE.

GUSTAF ARVID ANDERSON, OF BALTIMORE, MARYLAND, ASSIGNOR TO THE T. H. SYMINGTON COMPANY, OF NEW YORK, N. Y., A CORPORATION OF DELAWARE.

CAR TRUCK.

1,414,921.

Specification of Letters Patent.

Patented May 2, 1922.

Application filed January 25, 1921. Serial No. 439,811.

To all whom it may concern:

Be it known that I, GUSTAF ARVID ANDERSON, a citizen of the United States, residing at Baltimore, in the State of Maryland, have 5 invented certain new and useful Improvements in Car Trucks; and I do hereby declare the following to be a full, clear, and exact description of the invention, such as will enable others skilled in the art to which 10 it appertains to make and use the same.

The invention relates to car trucks of the type, called flexible trucks, in which the side frame members are capable of relative movement longitudinally of the truck, and is more 15 particularly concerned with the production of an improved type of flexible truck in which means are provided for resisting longitudinal displacement of either side frame from its normal or square position 20 and for returning the side frames to normal following their displacement out of square through the application of external forces thereto as a result of the passage of the truck around curves or over defective switch 25 points or imperfect rail joints.

The principal object of my invention, generally stated, is to afford compact, simple and efficient means for normally but yieldingly maintaining the side frames in square 30 relation and for returning them to square relation upon the cessation of the external force by which their displacement from normal is induced. To this end the principal feature of the invention consists in combining in a truck spaced side frame members which are relatively movable longitudinally, and means for yieldingly resisting relative longitudinal displacement of the frame members from normal position, 35 said means involving a spring and means for energizing said spring upon the relative longitudinal displacement of the side frames from normal position, the said spring energizing means having inflexibly united 40 rigid portions which are adapted to engage one of said side frame members at a plurality of spaced points on opposite sides of the center of said frame.

A further principal feature of the invention 45 consists in employing spaced side frame members which are relatively movable longitudinally of the truck and which are connected by cross connecting means pivotally attached to each of the frame members, and

by combining therewith a spring which is 55 compressible in the direction of the line connecting the said pivotal points and which is energized to resist an out of square displacement of the side frames upon the occurrence of such a displacement. A still 60 further primary feature of the invention resides in yieldingly resisting relative longitudinal displacement of the truck side frame members from normal position by means of a spring which is compressible from one end 65 thereof in response to longitudinal displacements of either of said side frame members in either direction from normal position.

There are other features of invention residing in the various elements and in combinations of elements as will hereinafter appear.

In the drawings illustrating the preferred embodiment of the invention, the scope 75 whereof is pointed out in the claims,

Figure 1 is a view, partly in plan and partly in horizontal section, of a car truck embodying the invention, the truck bolster and bolster springs, which may be like those 80 commonly employed in flexible trucks, being omitted, and the truck parts being illustrated in a position such as they assume when the truck is passing around a curve.

Fig. 2 is a detail view, partly in plan and partly in horizontal section, showing the relation of one of the side frame members to the member by which said side frames are movably connected transversely of the truck and to the yielding means for resisting relative longitudinal displacement of the side 90 frame members from normal, a portion of the cross connecting member being broken away to disclose the said yielding means.

Figure 3 is a detail sectional view on the line 3—3, Fig. 2.

Figure 4 is a section on the line 4—4, Fig. 2, looking toward the adjacent side frame.

Figure 5 is a section on the line 5—5, Fig. 2, looking toward the adjacent side frame member.

Figure 6 is a section on the line 6—6, Fig. 2, looking away from the adjacent side frame.

In the drawings, 1 indicates transversely spaced side frame members which are adapted to have a relative movement longitudinally of the truck. Each side frame member is furnished at its opposite ends with

journal boxes 2 receiving the journal ends of axles 3 upon which the truck wheels 4 are mounted.

The side frames 1 are movably connected 5 across the truck by cross connecting means 5 which may advantageously be a spring plank member whose opposite ends project into the centrally located bolster openings 6 of the respective side frames between the columns 10 7 of the latter. The sides of the spring plank 5 are spaced from the adjacent truck columns 7 a sufficient distance to afford proper clearance enabling the spring plank to change its angular relation with respect 15 to the side frames without binding upon the said columns when the frame members 1 are subjected to an extended displacement from normal or square relation. The truck bolster (not shown) is, as is usual in flexible trucks, 20 suitably spaced from the truck columns 7 to permit the bolster freely to change its angular position horizontally in response to longitudinal displacements of the side frame members 1. A convenient means of mov- 25 ably connecting the spring plank 5 with each of the side frame members 1 consists in providing each of said frame members at the center of its bolster opening 6 with an upwardly projecting pivot boss 8 which enters 30 a correspondingly formed aperture 9 in the adjacent end of the spring plank.

It is preferred to employ a plurality of means 10 for yieldingly resisting relative longitudinal displacement of the side frame 35 members 1 from normal position and for restoring said side frames to square relation, said means each being associated with a neighboring frame member 1 and being rigidly mounted upon the cross connecting 40 means 5 in spaced relation. Each yielding mechanism 10 preferably includes a housing 11 which may be rigidly secured to the under side of the spring plank 5 by means of rivets 12. The housing 11 is preferably provided 45 with a single spring pocket 13 for receiving a transversely extending spring 14 which is compressible in the direction of the line on which the pivots 8 of the truck lie. The spring receiving pocket or recess 13 is pref- 50 erably open at the top to permit the introduction of the spring which may be advantageously assembled under an initial compression offering resistance sufficient to maintain the side frames 1 in square under 55 normal operating conditions, but allowing the truck parts to yield momentarily to cushion and relieve abnormal shocks.

The spring 14 whose inner end is seated upon the rear wall 15 of the housing, is 60 adapted to be compressed by a rigid unitary operating member or plunger 16 which reciprocates parallel to the spring plank 5 and engages the adjacent side frame mem- 65 ber 1. The plunger 16, which enters and preferably extends entirely through the

housing 11, may be shouldered to form an integral follower 17 which engages the outer end of the spring. The part of the plunger which engages the adjacent side frame 1 is formed with oppositely extending inflexibly 70 united rigid portions or arms 18 which are adapted to engage said side frame on opposite sides of its pivot boss 8. To cause the plunger 16 to reciprocate parallel to the spring plank 5 and to prevent it from rotating about its axis of reciprocation, the upper end of the follower portion 17 is preferably provided with flat faces or shoulders 19, and the stem of the plunger may be formed at its rear end with a vertically ex- 75 tendsing lug or offset 20 whose upper end conforms to the bottom of the spring plank. For a similar purpose the lower portions 21 of the plunger stem in advance of the follower 17 are arranged in contact or sub- 80 stantially in contact with the upper surface of the horizontally extending wall 22 with which the housing 11 is provided at its outer end. By the engagement of the under side 85 of the spring plank 5 with the faces 19 of the follower 17 and with the upper end of the offset projection 20, and by the engagement of the lower faces 21 of the plunger stem with the upper surface of the wall 22 of the housing 11, the spring operating plunger 90 or member 16 is prevented from rotating upon its axis and is required to slide in parallel or substantially parallel relation to the spring plank 5.

As shown in Fig. 4, the sides of the inner 100 end portion of the plunger 16 stand closely adjacent to the neighboring end wall 15 of the housing 11; and as shown in Fig. 5, the side walls 23 of the follower 17 are likewise disposed closely contiguous to the neighboring side walls of the housing 11. This construction affords a convenient means for preventing relative horizontal shifting or twisting of the plunger 16 with respect to the housing 11.

When the side frame members 1 are displaced longitudinally of the truck from normal relation as occurs, for example, when the truck passes around a curve, the spring plank 5 or means movably connecting the 115 side frames across the truck shifts its angular relation with respect to the frame members. This change in the angular relation of the spring plank to the side frames results in pressure being exerted on the 120 plunger 16 through one of its rigid arms 18, and causes the plunger to slide inwardly in the housing 11, thereby compressing the spring 14 between the follower 17 of the plunger and the inner end wall 15 of the hous- 125 ing. Upon cessation of the external force causing the relative longitudinal displacement of the side frame members 1 from normal position, the energy stored in the spring 14 forces the plunger back to normal posi- 130

tion, thereby causing the spring plank 5 and the side frames 1 to be restored to their normal position. If the side frame is displaced in the opposite direction from normal position the operation is precisely the same as heretofore described, except that pressure is delivered from the side frame to the plunger 16 and thence to the spring 14 through the other arm 18 of the plunger.

10 It will be apparent that instead of using a plurality of yielding means 10 for opposing displacement of the truck parts from normal relation, and for restoring them to square position, a single yielding mechanism

15 may be employed for that purpose, since a horizontal angular change of the spring plank from its normal position results in energizing the springs 14 of both yielding mechanisms and, conversely, the restoration

20 of the spring plank 5 to normal position by either yielding mechanism 10, necessarily returns the side frames to square relation.

I claim:—

1. In a car truck, the combination with
25 transversely spaced side frame members which are relatively movable longitudinally of the truck, of means for movably connecting said side frame members across the truck, and means for yieldingly resisting
30 relative longitudinal displacement of said side frame members, said last named means involving a spring and unitary means co-operating with an adjacent one of said side frame members for energizing said spring
35 upon displacement of said adjacent frame member longitudinally in either direction from its normal position.

2. In a car truck, the combination with
40 transversely spaced side frame members which are relatively movable longitudinally of the truck, of means for pivotally connecting said side frame members across the truck, and means for yieldingly resisting relative longitudinal displacement of said side frame
45 members, said last named means involving a spring, and means cooperating with an adjacent one of said side frame members for energizing said spring upon displacement of said adjacent frame member longitudinally in either direction from normal position, said spring energizing means having inflexibly united rigid portions adapted to engage said adjacent side frame member on opposite sides of its pivotal connection
55 to said cross connecting means.

3. In a car truck, the combination with
transversely spaced side frame members
which are relatively movable longitudinally
of the truck, of means for pivotally connect-
60 ing said frame members, and means for
yieldingly resisting relative longitudinal
displacement of said frame members from
normal position, said last named means in-
volving a spring extending transversely of
65 the truck, and means for energizing said

spring upon displacement of the adjacent side frame member longitudinally in either direction from normal position, said spring energizing means having inflexibly united rigid portions adapted to engage said adjacent side frame member on opposite sides of its pivotal connection to said means by which said frame members are connected.

4. In a car truck, the combination with
transversely spaced side frame members
which are relatively movable longitudinally
of the truck, of means for movably connect-
ing said side frame members, and means for
yieldingly resisting relative longitudinal
displacement of said side frame members from
normal position, said last named means in-
volving a spring, and means coacting with
an adjacent one of said side frame members
and adapted to reciprocate transversely of
the truck to energize said spring upon lon-
gitudinal displacement of said adjacent side
frame member in either direction from nor-
mal position.

5. In a car truck, the combination with
transversely spaced side frame members
which are relatively movable longitudinally
of the truck, of means for movably connect-
ing said side frame members, a spring ex-
tending transversely of said truck, and
means interposed between said spring and
an adjacent one of said side frame members
for energizing said spring upon a longitu-
dinal displacement of said adjacent frame
member in either direction from normal po-
sition.

6. In a car truck, the combination with
transversely spaced side frame members
which are relatively movable longitudinally
of the truck, of cross connecting means piv-
otally connected to each of said side frame
105 members, a spring compressible on a line
connecting said pivotal points, and means
for compressing said spring upon a relative
longitudinal displacement of said frame
members from normal position.

7. In a car truck, the combination with
transversely spaced side frame members
which are relatively movable longitudinally
of the truck, of means for movably connect-
ing said side frame members, and means co-
operating with one of said side frame mem-
bers for yieldingly resisting relative longitu-
dinal displacement of said frame members
from normal position, said last named
means involving a single spring only which
115 is adapted to be energized by a longitudinal
movement of one of said side frame mem-
bers in either direction from its normal po-
sition.

8. In a car truck, the combination with
transversely spaced side frame members
which are relatively movable longitudinally
of the truck, of cross connecting means piv-
otally connected to each of said side frame
members, and means for yieldingly resisting
120

relative longitudinal displacement of said frame members from normal position, said last named means involving a spring, and a plunger for energizing said spring, said 5 plunger being adapted to engage one of said side frame members on opposite sides of the point of pivotal connection of said frame member to said cross connecting means.

9. In a car truck, the combination with 10 transversely spaced side frame members which are relatively movable longitudinally of the truck, of means for movably connecting said side frame members, and means for yieldingly resisting relative longitudinal 15 displacement of said side frame members from normal position, said last named means involving a spring, a reciprocating plunger adapted to energize said spring upon longitudinal displacement of one of 20 said side frame members in either direction from normal position, and means for preventing rotation of said plunger about its axis of reciprocation.

10. In a car truck, the combination with 25 transversely spaced side frame members which are relatively movable longitudinally of the truck, of a spring plank pivotally connected to each of said side frame members, and means mounted upon said spring 30 plank for yieldingly resisting relative longitudinal displacement of said frame members from normal position, said yielding means involving a housing secured to said spring plank, a spring within said housing, 35 and a plunger adapted to reciprocate parallel to said spring plank and operatively interposed between the latter and one of said side frame members and adapted to energize said spring upon a longitudinal 40 displacement of said side frame member in either direction from its normal position.

11. In a car truck, the combination with

transversely spaced side frame members which are relatively movable longitudinally of the truck, of means for movably connecting said side frame members, and means for yieldingly resisting relative longitudinal displacement of said frame members from normal position, said last named means involving a spring which is compressible from one end thereof in response to longitudinal displacements of one of said side frame members in either direction from its normal position.

12. In a car truck, the combination with 55 transversely spaced side frame members which are relatively movable longitudinally of the truck, of means for movably connecting said side frame members, and means for resisting relative longitudinal displacement of said side frame members from normal position, said last named means involving a spring, and a reciprocating plunger for energizing said spring, said plunger having a stem and being adapted to engage 60 one of said side frame members at a plurality of spaced points on opposite sides of the center of said frame member and being provided with means for actuating said spring and having a portion adapted slidably to engage said connecting means.

13. In a car truck, the combination with 70 transversely spaced side frame members which are relatively movable longitudinally of the truck, of cross connecting means pivotally connected to each of said side frame members, a spring compressible transversely of the truck, and means for compressing said spring upon the relative longitudinal displacement of said side frame members 80 from normal position.

In testimony whereof I affix my signature.

GUSTAF ARVID ANDERSON.
